UNITED STATES PATENT OFFICE.

ROBERT ROADHOUSE, OF DES PLAINES, ILLINOIS, ASSIGNOR OF ONE-HALF TO
THOMAS E. McCAG, OF CHICAGO, ILLINOIS.

METHOD OF ENAMELING WARE.

1,395,732.

Specification of Letters Patent.

Patented Nov. 1, 1921.

Application filed March 9, 1921. Serial No. 450,862.

To all whom it may concern:

Be it known that I, ROBERT ROADHOUSE, a citizen of the United States, residing at Des Plaines, in the county of Cook and State of Illinois, have invented a new and useful Improvement in Methods of Enameling Ware, of which the following is a specification.

This invention relates to a method of 10 enameling ware and to furnaces for practising the same.

The primary object of this invention is to provide a furnace for enameling and the like having a main enameling chamber 15 which is heated directly by fuel instead of by the indirect method used in the well known muffle type of furnace.

This object can be accomplished by this invention which consists in a furnace having a main enameling chamber which is heated directly by burning fuel therein and which has means for scavenging the gases of combustion before the objects to be enameled are introduced therein, so that the 25 enamel will not be injured thereby.

Referring now to the drawings, Figure 1 is a rear elevation of the furnace;

Fig. 2 is a side elevation of the same;

Fig. 3 is a vertical longitudinal section 30 on the broken line 3—3 of Fig. 1;

Fig. 4 is a vertical transverse section on the line 4—4 of Fig. 3; and

Fig. 5 is a horizontal section on the broken line 5—5 of Figs. 2 and 3.

The furnace consists of a chamber 10 formed by the side walls 11, the bottom 12 and the arch top 13. It is closed at the rear by the rear wall 14, except for the firing opening 15 and at the front by the front wall 16 and the sliding door 17. A flue 18 feeds from the rear of the furnace as shown in Figs. 3 and 4 and connects with a stack (not shown). This flue may be closed as will later be explained by means of the 45 valve 19. The side walls are reinforced in the usual manner by means of buck stays 20 and rods 21.

The front door 17 is slidable up and down in suitable guide-ways 22 and is raised by 50 means of a rope 23 passing over suitable pulleys 24. This rope is connected to the piston rod 25 which is attached to a piston 26 which is operable in the cylinder 27. Steam or air is introduced into this cylinder 55 through pipes 28 and 29 from any suitable

source of supply. A counter-weight 30 is attached to the lower end of the piston-rod 25 for counter-balancing the door 17.

The lower part of the furnace is divided into two compartments 31 and 32 by means 60 of the wall 33 which is preferably raised to the level of the ledges 34.

A burner 35 is placed in front of each of the openings 15 and is supplied with oil or other fuel from a suitable source through 65 the pipe 36. Air from a suitable source is likewise introduced through the pipe 37, and the pressures of both the oil and the air at the burner are regulated by suitable valves. Preheating coils 38 and 39 are located in the walls of the furnace for heating the oil and air respectively before they are fed to the furnace. Quick opening valves 40 and 41 are placed in the oil and air line which have operating levers 42 and 43 70 respectively which are connected by means of rods 44 and 45 with levers 46 which are secured to the shaft 47.

This shaft is journaled in suitable bearings at the rear of the furnace and carries 80 a lever arm 48 which is operable by the rod 49, the lever 50 and the rod 51 from the front of the furnace.

It will be seen from the foregoing that the valves 40 and 41 may be opened and 85 closed simultaneously from the front of the furnace. Sliding doors 52 cover the openings 15 and these are connected by means of rope 53 with lever arms 54 which are secured on the shaft 47, so that as the valves 40 and 41 are opened the doors 52 will be raised, uncovering the openings 15. In the same way the flue valve 19 as shown in Fig. 2 is connected to the lever 50 by means of a rope 55 passing over pulleys 56 and the crank 90 arm 57. This arm also carries a weight 58 for counter-weighting the doors 19 and 52.

The operation of the device is as follows:

Starting with the parts in the positions shown in Fig. 3, the burners 35 operating 100 under compressed air are forcing a powerful flame over the ignition blocks 59 and along the walls of the compartments 31 and 32. The hot gases are deflected upwardly and backwardly by the end wall 16 and 105 passed back through the top of the furnace chamber and out through the flue 18.

As soon as the desired temperature is reached the rod 51 is pushed to the right as shown in Fig. 2, shutting off the burners 35 110

and dropping the doors 19 and 52, thereby closing the openings 15 and the flue 18. The door 17 is then raised to permit of the furnace being charged and cold air rushing in through the bottom of the opening, forces out the burned gases through the top of the opening, thereby scavenging the enameling chamber. The material to be enameled has previously been placed upon crates or frames and these are brought in on the track 60 and are introduced through the front opening and deposited upon the ledges 34 and the top of the central wall 33. The door 17 is then closed and the crates are left within the furnace the desired length of time to bake the enamel.

The door 17 is then raised and the crates removed and the door 17 again lowered. The rod 51 is again pulled to the left to the 20 full line position shown in Fig. 2, opening the doors 19 and 52, and valves 40 and 41, thereby throwing a combustible mixture from each of the burners 35 against the ignition blocks 59. These retain a great 25 deal of the heat which they previously had and cause this combustible mixture to ignite. When the desired temperature is again reached the burners 35 are shut off and the doors 19 and 52 closed as before.

30 While have shown and described but a single embodiment of my invention, it is to be understood that it is capable of many modifications. Changes, therefore, in the construction and arrangement may be made 35 without departing from the spirit and scope of the invention as disclosed in the appended claims, in which it is my intention to claim all novelty inherent in my invention as broadly as possible in view of the prior art.

40 What I claim as new and desire to secure by Letters Patent is:

1. In a furnace for enameling and the like, a chamber, means for producing combustion

therein, control means for stopping said combustion, means for scavenging the products of combustion and means for closing the chamber during the baking operation. 45

2. In a furnace for enameling and the like, a chamber, means for producing combustion therein, control means for stopping said 50 combustion, and a door opening to admit air to said chamber for scavenging the same when the furnace is being charged with ware to be burned and closing to seal said chamber during the baking operation. 55

3. In a furnace for enameling and the like, a chamber, means for producing combustion therein, control means for stopping said 60 combustion, and a door near the top of said chamber opening to admit air to said chamber for scavenging the same when the furnace is being charged with ware to be burned and closing to seal said chamber during the baking operation. 65

4. In a furnace for enameling and the like, a chamber having an opening, a burner for producing combustion therein, control means for starting and stopping said combustion, a flue, doors operably connected to said control means and movable as combustion in the burner is stopped, to close said flue and opening, and means for scavenging 70 said chamber of the products of combustion. 75

5. The method of enameling ware consisting of producing combustion directly in the enameling chamber, scavenging the products of combustion and introducing the objects to be enameled into said chamber. 80

6. The method of enameling ware consisting of producing combustion directly in the enameling chamber, scavenging the products of combustion, introducing the objects to be enameled into said chamber and closing said chamber. 85

ROBERT ROADHOUSE.
